[57] CLAIM

The ornamental design for a shoe, as shown and described.

DESCRIPTION

FIG. 1 is a left side elevational view of a shoe showing our new design;

FIG. 2 is a right side elevational view thereof;

FIG. 3 is a front elevational view thereof;

FIG. 4 is a rear elevational view thereof;

FIG. 5 is a top plan view thereof;

FIG. 6 is a left side elevational view of a shoe showing a modified form of our new design;

FIG. 7 is a right side elevational view thereof;

FIG. 8 is a front elevational view thereof;

FIG. 9 is a rear elevational view thereof; and

FIG. 10 is a top plan view thereof.

The bottom of the shoe, not shown, is substantially plain and conventional.

The solid and broken line cross hatched portions of the shoe respectively are in contrasting chromatic colors, the solid line cross hatched portions being shown in green and the broken line cross hatched portions being shown in purple.
